RETAINER FOR OSCILLATING MOISTENING
ROLL SHAFTEdward J. Janke, Cleveland, Ohio, assignor to
Addressograph-Multigraph Corporation, Cleve-
land, Ohio, a corporation of Delaware

Application June 14, 1949, Serial No. 99,076

6 Claims. (Cl. 287—20)

1

This invention relates to retaining devices and more particularly to a retaining device adapted for use in a rotary offset lithographic printing machine wherein a lithographic master, from which impressions are to be made, is mounted on the periphery of a drum in the machine and to which master a repellent solution and ink are applied in succession.

The lithographic master used in printing machines of the aforesaid character bears an ink receptive image that picks up ink as the master runs into contact with rollers included in an ink supply means in the machine. A repellent solution is supplied to the unimaged portion of the plate and collects thereon and is effective to preclude the ink from adhering to anything other than the ink-receptive image.

It has been customary to supply ink to the master in printing machines of the aforesaid character from a fountain, into which the ink is introduced, through a series of rollers of which one operates in the fountain to pick up ink therefrom. Usually a transfer roller is provided in the train in spaced relation with the fountain roller and still another roller is interposed between the fountain and transfer rollers and operates to move from peripheral contact from one of such rollers into peripheral contact with the other, such a movable roller being commonly known as a doctor roller. The train of rollers that is effective to supply the ink to the image also includes one or more rollers which are disposed in such position as to roll over the master bearing the image as this master comes into contact with these rollers in the course of operation of the machine. The rollers which are thus effective to supply ink to the images on the masters are known as form rollers. A train of rollers of the aforesaid character also usually includes therein, intermediate the doctor roller and the form roller or rollers, a roller to which a longitudinal or axial as well as a rotary movement is imparted and such roller is commonly referred to as an oscillating distributor roller, the purpose of this roller being to insure uniform distribution of the ink along the periphery of the rollers and especially along the periphery of the form roller or rollers.

The repellent solution is supplied to the unimaged portions of the master through an arrangement similar to the ink supply means. Thus, this arrangement includes at least one roller which is disposed in position to ride on the surface of the lithographic master as it moves thereby in the operation of the machine, such a

2

roller also being known as a form roller. In addition to such a form roller, the arrangement or train supplying repellent to the master customarily includes a fountain into which the repellent solution may be introduced and also a roller disposed in position to pick up repellent from the fountain, this roller being known as the fountain roller. The repellent supply arrangement also includes a doctor roller which is effective to transfer repellent from the fountain roller to a distributing roller which is usually disposed in peripheral engagement with the form roller or rollers to supply the repellent solution thereto. In some instances, such a distributing roller is arranged for merely rotary movement but in other instances it has been found to be desirable to impart a longitudinal or axial as well as a rotating movement to such a distributing roller since so to do insures uniform distribution of the repellent especially over the form roller or rollers. Where such a distributing roller is arranged to have longitudinal as well as rotative movement imparted thereto, it is commonly known as an oscillating distributor roller and it corresponds in function and arrangement to the oscillating distributor roller customarily employed in an ink supply arrangement as described hereinabove.

Especially in arrangements of the aforesaid character for supplying repellent to a lithographic master it has been found to be advantageous to insure that the distributing roller remains in firm engagement with the form roller so as to insure uniform distribution of the repellent solution over and about the surface of the form roller. Moreover, it is advantageous in printing machines of the aforesaid character to enable such a distributing roller to be readily removed from the machine. In some machines of the aforesaid kind it is necessary to arrange for expeditious removal of the distributing rollers since, in such machines, the distributing rollers are mounted above and over the form rollers. Removal of the form rollers from time to time is usually necessary for it is customary to provide a moisture absorbent felt, such as molleton, on the periphery of such a roller and such a covering is removed and replaced from time to time so as to insure that clean reproductions will be produced in the printing machine.

In view of the foregoing, it is the object of my invention to afford a novel arrangement that will be effective to retain a distributing roller of the aforesaid character or the like in firm but yielding engagement with another roller, such

as a form roller in an ink or repellent train. So to do eliminates undesired separation of the rollers and precludes bouncing of one roller on the other roller, any such bouncing having been found to be particularly disadvantageous in the repellent train of a printing machine of the aforesaid character.

Other objects of the invention are to retain a distributing roller or the like in firm but yielding contact with another roller and yet enable the retained roller to be expeditiously removed from the machine when and if desired; and to so retain such a roller by resort to an arrangement so fixed in retaining position as to insure against accidental misplacement thereof.

Still other objects are to utilize an arrangement that may be permanently connected to the machine and which may be effective to limit longitudinal or axial movement of a distributor roller or the like relative to the portions in the machine in which the roller is mounted; to enable the firm but yieldable engagement between rollers of the aforesaid character to be expeditiously adjusted when and if desired; and to enable a portion of a roller retaining arrangement of the aforesaid character to be moved to and retained in an ineffective position where such portion will not interfere with removal of the retained roller from the machine.

Other and further objects of the present invention will be apparent from the following description and claims and are illustrated in the accompanying drawing which, by way of illustration, show preferred embodiments of the present invention and the principle thereof and what I now consider to be the best mode of applying that principle. Other embodiments of the invention embodying the same or equivalent principles may be used and structural changes may be made as desired by those skilled in the art without departing from the present invention and the purview of the appended claims.

In the drawing:

Fig. 1 is a fragmentary perspective view of an offset lithographic printing machine in which my invention has been incorporated;

Fig. 2 is another fragmentary perspective view, drawn to a scale larger than Fig. 1, and showing the retaining element of my novel roller retaining arrangement in the effective roller retaining position thereof;

Fig. 3 is a fragmentary side elevational view wherein the retaining element of my roller retaining arrangement is shown in the ineffective position thereof;

Fig. 4 is a vertical sectional detail view taken substantially on the line 4-4 on Fig. 3 but wherein the retaining element of the roller retaining arrangement is shown in the effective position thereof;

Fig. 5 is a horizontal sectional view taken substantially on the line 5-5 on Fig. 4; and

Fig. 6 is a view similar to Fig. 4 but showing a modified form of my arrangement and wherein the various elements of my arrangement are shown in elevation.

The embodiment of my invention shown in Figs. 1 to 5 of the accompanying drawing is illustrated in association with an offset lithographic printing machine of the kind disclosed in Morse Patent No. 2,065,535, patented December 29, 1936, and particularly the arrangement for supplying repellent to a lithographic master mounted on one of the rotary drums in the machine is in the nature of that disclosed in this patent. The ma-

chine as illustrated includes a frame generally indicated by F having brackets 10 and 11 mounted thereon which afford a support for the repellent supply arrangement. This arrangement includes 5 a trough 13 into which a supply of liquid repellent is introduced either manually from time to time or through an automatic source of supply such as that disclosed in aforesaid Patent No. 2,065,535. A roller 14 is mounted for rotative movement in 10 position to pick up from the trough 13 liquid repellent introduced thereinto and a rotatable and movable ductor roller 15 is suitably supported in the machine to be bodily movable, in a reciprocatory manner, between, and so as to have alternate 15 peripheral contact with, the fountain roller 14 and an oscillating distributing roller 16, one means suitable for effecting such reciprocatory movement of the ductor roller 15 being disclosed in the aforesaid patent. The distributing roller 20 16 is mounted above and in position to have peripheral engagement with a form roller 17 mounted so as to roll upon the surface of a lithographic master in the course of operation of the printing machine. The form roller 17, as in the 25 instance of other elements referred to hereinabove, is in the nature of that disclosed in aforesaid patent and is set in rotation in the manner disclosed in that patent.

As is customary in the art, the form roller 17 30 desirably has a removable moisture absorbent felt, such as molletin, on the periphery thereof which is usually in the nature of a sleeve and which sometimes may have a seam running longitudinal thereof. I have observed, where such a 35 covering is included on a form roller as 17 and the covering has a longitudinal seam therein, that if the distributing roller is not held in firm but yielding engagement with the form roller in the course of rotation of the rollers, the distributing roller may be forced upwardly away from the form roller as the seam passes the distributing roller and after the seam is once passed with the normal periphery of the form roller 17. 40 This, in some instances, has resulted in the distributing roller bouncing on the form roller and this has been found to be objectionable in printing machines of the kind in which my invention is embodied. I have, therefore, provided an arrangement for maintaining the distributing roller 16 in firm but yielding engagement with the form 45 roller 17.

In aforesaid Patent No. 2,065,535 the distributing roller that contacts the form roller is described as having a layer of felt or more moisture absorbing material, such as molletin, secured thereon. However, in an instance such as the present, where the distributing roller is to have longitudinal as well as rotary movement imparted thereto, it has been found to be advantageous to 55 eliminate such a covering so that in the present instance the periphery of the distributing roller 16, that is to engage the form roller 17 and be engaged by the ductor roller 15, is preferably rubber or other resilient but non-absorptive material or in some instances metallic.

In the present instance rotary movement is 60 imparted to the roller 16 by the peripheral engagement thereof with the form roller 17 which, as is customary in the art, is positively driven through the intermediary of gears and the like in timed relation with other operative parts in the machine including the drum on which the lithographic master is mounted. Longitudinal 65 movement may be imparted to a distributing

roller as 16 in different ways but in the present instance the assembly of which the roller 16 is a part includes a non-rotatable shaft 18 and an arrangement such as that disclosed in Morse Patent No. 2,006,364, patented July 2, 1935, is utilized to impart the desired longitudinal movement. Thus, a hub as 19 is fast to the shaft 18 inwardly of each end thereof. A cam groove (not shown) is provided in the periphery of such a hub. The peripheral portion of the shaft 18 is afforded by a shell or sleeve mounted for rotative and slideable movement on the hubs as 19. The shell has a cam follower (not shown) in the form of a roller or the like, mounted interiorly thereof and this follower rides in the cam groove provided in the hub as aforesaid. The configuration of the cam groove is such that as the cam roller or the like travels therethrough, a reciprocatory motion is imparted to the periphery of the distributing roller 16 in the course of rotative movement thereof. It will be understood that resort may be had to arrangements other than the foregoing to impart the reciprocatory as well as rotative movement to at least the peripheral portion of a distributing roller as 16 since such means are not a part of my present invention.

Where, as in the present instance, the oscillatory distributing roll assembly includes a stationary shaft as 18, it is advantageous to provide a recess as 20 in each of the brackets 10 and 11 in such positions that when the outwardly extending end portions of the shaft as 18 are disposed in such recesses, the periphery of the distributing roller as 16 will be disposed in position to ride on a form roller as 17 and also in position to be engaged by a doctor roller as 15 at the end of reciprocatory movement of this latter roller in one direction. Portions at each end of the shaft 18 are cut away along chords to afford a flattened end portion as 21 at each end of the shaft. These flattened end portions have shoulders as 22 at the inner ends thereof and, when the flattened end portions as 21 are respectively disposed in the recesses as 20 in the brackets as 10 and 11, these shoulders respectively engage the adjacent portions of the inner faces of the brackets as 10 and 11 and thereby the shaft as 18 is held against longitudinal or axial movement in the machine.

It has been explained hereinabove that it is desirable to maintain a distributing roller as 16 in firm but yielding engagement with a form roller as 17. Moreover, especially when a distributing roller as 16 is to have reciprocatory as well as rotative movement imparted thereto, it is necessary that the shaft 18 be retained against rotative movement. I have, therefore, provided an arrangement which will so retain a shaft as 18 and this arrangement is of such nature that a portion thereof may be moved to and retained in an ineffective position so as to thereby enable installation in, or removal of, a distributing roller as 16 into and from the machine when and if desired. In Figs. 2 to 5 of the drawing I have shown the arrangement which is provided for the end of the shaft 18 that is disposed in the recess 20 afforded in the bracket 10 and it will be understood that, in the present instance, a similar arrangement is provided for association with the end of the shaft 18 mounted in the recess 20 in the bracket 11.

The arrangement illustrated in Figs. 2 to 5 includes an annular post member 23 which is screw threaded at one end thereof as indicated

at 24. An adjusting nut 34, explained hereinafter, is mounted for movement along the screw threads 24 and a cap nut 25 cooperates with the screw threads 24 to be secured on the adjacent end of the post 23. The post is also screw threaded at the other end thereof so that it may be threaded into the tapped opening 27 provided in the lower wall of the recess 20. In the present instance the opening 27 is located substantially midway between the side walls of the recess 20 and also substantially midway between the opposite faces of the bracket 10. The post 23 is firmly mounted in the tapped opening 27 to insure against undesired displacement thereof. A retaining element, generally indicated by 28, has a bore 29 extending therethrough which is of a diameter slightly greater than the diameter of the post 23 so that the element 28 is freely movable along the post. The retaining element has an annular collar portion 30 at the upper end thereof, the periphery of which is preferably knurled. The body 31 of the retaining element, below the collar portion 30 thereof, is of a length equal to the diameter of such collar portion but is of restricted width relative to such diameter and this body includes opposed flat surfaces or faces 32 so the body 31 is, in effect, elongated but of restricted width. This restricted width of the body 31, enables it to freely pass into a recess as 20 but the length of the body 31 is greater than the width of the recess 20 so as to enable the retaining element to be disposed and retained in an ineffective position, as will be described.

A spring 33 is disposed about the post 23 between the adjusting nut 34 and the collar portion 30 and is effective to urge the retaining element 28 downwardly on the post 23 when the threaded portion 26 has been fast in the tapped opening 27.

When it is desired to mount the shaft 18 of the roller assembly 16 in the machine, the retaining element 28 is moved upwardly along the body of the post 23 against the effect of the spring 33 and the retaining element is also so rotated into position with respect to the body of the post that one of the flat surfaces 32 thereon is disposed to face inwardly of the machine and be in at least substantially parallel relation with the adjacent end of the shaft as 18 that is to be disposed in the recess as 20 in which the post is mounted. When the retaining element is so oriented relative to the post 23, the flat surfaces 32 thereof will be in substantially parallel relation with the side walls of the bracket as 10. When the flat surfaces 32 are in this position, the end portions of the body 31 extend over the free edges of the marginal portions of the side walls of the recess 20. When the retaining element is disposed in this position and is freed to the influence of the spring 33, the lower edge of the element 28 is urged toward the upper edge of the bracket as 10 and the end portions of the body 31 of the element may then rest upon the upper free edges of the marginal portions of the side walls of the recess 20 in which the post as 23 is mounted, the various elements being shown in this position in Fig. 3. When a retaining element as 28 is disposed in this just described position, it is retained in an ineffective position and the adjacent end portion as 21 of a shaft as 18 may be freely moved inwardly and outwardly of the recess as 20 adapted to receive the same since the body portion 31 will be out of alignment with the end portion as 21.

When the end portions as 21 have been introduced into the recesses at a time when the retaining elements are held in the aforesaid ineffective positions thereof, the periphery of the roller 16 engages and rests upon the periphery of the form roller 17. When this occurs, one of the flat faces of the adjacent end portion 21 of the shaft as 18 may rest upon the lower wall of the recess 20 dependent upon the relation established among the various parts. In some instances, however, the lower of the flat faces of the end portion 21 will be disposed in spaced relation with the lower wall of the recess 20 in which the end portion is disposed. After the end portions 21 of the shaft 18 have been arranged in the recesses 20 in the just described manner, the retaining elements as 28 may be raised against the effect of the springs 33 and the element is then rotated so as to present the flat faces 32 in substantially parallel relation with the side walls of the recess 20 in which the retaining element is mounted. Thereupon the body 31 of the retaining element 28 is free to enter the recess and when the body 31 is inserted into the recess and freed to the effect of the spring 33, one end portion thereof comes to rest upon one of the flat faces on the end portion 21 of the shaft 18. When the retaining elements as 28 are thus disposed in effective position so as to be engaged with the adjacent end portions 21 of the shaft 18, the springs 33 are effective to urge the roller 16 into firm but yielding engagement with the form roller as 17. In such circumstances, the nut 34 may be moved along the screw threaded portion 24 of the post as 23 so as to thereby vary the length and, therefore, the effectiveness of the adjacent spring as 33. Each nut as 34 is moved into such an adjusted position as to cause the associated spring as 33 to exert the proper degree of pressure on the roller as 16. Desirably the pressure thus exerted on the roller 16 is sufficient to hold the periphery of this roller 16 in firm but yielding engagement with the periphery of the form roller as 17 and such pressure is also desirably sufficient to insure against bouncing of the roller 16 relative to the roller 17.

When it is desired to remove an oscillating distributor roller assembly as 16 from the machine, each of the retaining elements as 28 is moved upwardly against the effect of the springs 33 and each element is rotated so as to be in the position of the retaining element 28 shown in Fig. 3 where the retaining element is disposed and retained in an ineffective and out-of-the-way position. Since the adjacent free end of the adjacent end portion 21 of the shaft is out of alignment the adjacent flat face 32 of the co-operating retaining element once the element is disposed and retained in its aforesaid ineffective position, the shaft as 18 may be freely moved into or out of the recesses as 20.

The modified form of my retaining arrangement shown in Fig. 6 is quite similar to that shown in Figs. 2 to 5 and in those instances where the elements shown in Fig. 6 correspond to those shown in Figs. 2 to 5, the reference character employed in Figs. 2 to 5 is applied to the corresponding element in Fig. 6 but the suffix "A" is added thereto. The modified form of my arrangement shown in Fig. 6 is one which is effective to not only maintain a roller as 16A in firm but yielding engagement with a form roller but this retaining arrangement is also so constructed as to enable it to be employed to limit endwise or axial movement of the shaft as 18A.

To this end, and as shown in Fig. 6, the lower

end of the post member 23A is enlarged as indicated at 35 so as to be of a diameter greater than that of the remaining extent of the post member. As in the instance of the post member 23A the lower end of the enlarged portion 35 is screw threaded, as indicated at 26A, so as to enable the same to be firmly mounted in a tapped opening as 27A. The diameter of the enlarged portion 35 and the end portion 21A of the shaft as 18A are so related one to the other that, when the free end of the end portion 21A is engaged with the periphery of the enlarged portion 35 of the post member 23A, this post member is effective to limit axial movement of the shaft as 18A in one direction and, when an arrangement such as that just described is provided at the other end of the shaft as 18A, this arrangement is effective to hold the shaft as 18A against movement in the other longitudinal or axial direction.

As in the instance of the retaining element 28, when the retaining element 28A is introduced into the recess 20A and freed to the effect of the spring 33A, it is effective to hold the roller as 16A in firm but yielding engagement with a form roller or the like. Moreover, when the retaining element as 28A is raised against the effect of the spring as 33A and is disposed and retained in the ineffective position thereof, which corresponds to the ineffective position of the retaining element 28 as shown in Fig. 3, then because of the diameter of the enlarged portion 35 and the restricted width of the body 31A of the retaining element 28A, the adjacent end portion 21A of the shaft as 18A may be freely lifted out of the recess 20A.

While I have described each form of my retaining arrangement as being associated with an oscillating distributor roller in an arrangement for supplying repellent to a lithographic master mounted on the master drum or cylinder of a lithographic printing machine, it will be understood that either illustrated form of my retaining arrangement, or other modification thereof, may be advantageously employed to retain a distributing roller of this character in operative position in a machine whether or not the roller is arranged to have longitudinal or axial movement imparted thereto as well as rotative movement. Moreover, if desired, either illustrated form of my retaining arrangement, or other modification thereof, may be used in association with a distributing roller included in an arrangement for supplying ink to a lithographic master mounted on the master drum or cylinder in a lithographic printing machine. Furthermore, various forms of the arrangement which I have provided may be used in association with any roller that is to be mounted in recesses afforded in a bracket or machine frame and especially where it is desirable that the roller be capable of removal and installation in the machine from time to time. Yet further, in many instances, my novel retaining element may be associated in the above described manner with but one end of a shaft and in such circumstances the other end of the shaft may be retained in operative position in any desired and appropriate manner.

It will be manifest from the foregoing description that the retaining arrangement which I

have provided enables the hereinabove and related objects of this invention to be realized. Hence, while I have illustrated and described preferred embodiments of my invention, it is to be understood that these are capable of variation and modification and I, therefore, do not wish to be limited to the precise details set forth, but desire to avail myself of such changes and alterations as fall within the purview of the following claims.

I claim:

1. In an apparatus of the character described including a frame member having a recess therein, a roller including a shaft end disposed in said recess to be capable of movement inwardly and outwardly of the recess, a retaining arrangement including a post member fast in the bottom wall of said recess, a retaining element mounted on said post member for movement therealong and for rotation thereabout, said retaining element including a shaft engaging part of restricted width to enable such part to pass into the recess and engage the shaft end therein, and yieldable means effective on said retaining element to urge the same along the post member and its shaft engaging part into the recess to engage the shaft end disposed in said recess, said shaft engaging part being of sufficient length relatively to the width of said recess so that when the retaining element is moved upwardly against the effect of the yieldable means and rotated about said post member at least a portion of the lower edge of such shaft engaging part may be disposed above and rested on the free edge of the marginal portion along at least one edge of the recess, the yieldable means being effective on said retaining element to retain it in engagement with the free edge of such marginal part, the restricted width of said shaft engaging part being such as to enable the shaft end to be moved out of or into said recess when the lower edge of said shaft engaging part is engaged as aforesaid with the free edge of said marginal portion.

2. In an apparatus of the character described including a frame member having a recess therein, a roller including a shaft end disposed in said recess to be capable of movement inwardly and outwardly of the recess, a retaining element including a post member fast in the bottom wall of said recess and including an enlarged part disposed to be effective to limit axial movement of the roller shaft in one direction, a retaining element mounted on said post member for movement therealong and for rotation thereabout, said retaining element including a shaft engaging part of restricted width to enable such part to pass into the recess and engage the shaft end therein, and yieldable means effective on said retaining element to urge the same along the post member and its shaft engaging part into the recess to engage the periphery of the shaft end disposed in said recess, said shaft engaging part being of sufficient length relatively to the width of said recess so that when the retaining element is moved upwardly against the effect of the yieldable means and rotated about said post member at least a portion of the lower edge of such shaft engaging part may be disposed above and rested on the free edge of the marginal portion along at least one edge of the recess, the yieldable means being effective on said retaining element to retain it in engagement with the free edge of such marginal part, the restricted width of said part being such as to enable the shaft end to be moved out of or into said recess when the lower edge

of said shaft engaging part is engaged as aforesaid with the free edge of said marginal portion.

3. In an apparatus of the character described including a frame member having a recess therein, a roller including a shaft end disposed in said recess to be capable of movement inwardly and outwardly of the recess, a shaft retaining arrangement including a post member having means thereon at one end thereof directly and rigidly securing the same in the bottom wall of said recess, a retaining element mounted for movement along and for rotation about said post member, said retaining element including a shaft engaging part of restricted width to enable such part to pass into the recess and engage the shaft end, and yieldable means effective on said retaining element to urge the same along the post member and its shaft engaging part into the recess in which the post member is secured, the retaining element being of sufficient length relatively to the width of the recess, and the shaft engaging part so related to the width of the recess that when the retaining element is moved longitudinally against the pressure of said yieldable means to withdraw the shaft engaging part out of the recess and is then partially rotated to position its shaft engaging part out of registering alignment with the recess, the shaft engaging part will engage upon the free edge of a marginal portion of the recess, and the retaining element will be held in elevated position to enable movement of the shaft end out of and into the recess.
4. In an apparatus of the character described including a frame member having a recess therein, a roller including a shaft end disposed in said recess to be capable of movement inwardly and outwardly of the recess, a shaft retaining arrangement including a post member having means thereon at one end thereof directly and rigidly securing the same in the bottom wall of said recess, a retaining element mounted for movement along and for rotation about said post member, said retaining element including a shaft engaging part of restricted width to enable such part to pass into the recess and engage the shaft end, and yieldable means effective on said retaining element to urge the same along the post member and its shaft engaging part into the recess in which the post member is secured, the retaining element being of sufficient length relatively to the width of the recess, and the shaft engaging part so related to the width of the recess that when the retaining element is moved longitudinally against the pressure of said yieldable means to withdraw the shaft engaging part out of the recess and is then partially rotated to position its shaft engaging part out of registering alignment with the recess, the shaft engaging part will engage upon the free edge of a marginal portion of the recess, and the retaining element will be held in elevated position to enable movement of the shaft end out of and into the recess.
5. In an apparatus of the character described including a frame member having a recess therein, the bottom wall of said recess being provided with a tapped opening therein, a roller including a shaft end disposed in said recess to be capable of movement inwardly and outwardly of the recess, a shaft retaining arrangement including a post member having a screw threaded part at one end thereof mounted in said tapped opening in the bottom wall of the recess, a retaining element mounted for movement along and for rotation about said post member, said retaining ele-

ment including a shaft engaging part of restricted width to enable such part to pass into the recess and engage the shaft end, and yieldable means effective on said retaining element to urge the same along the post member and its shaft engaging part into the recess in which the post member is secured, the retaining element being of sufficient length relatively to the width of the recess, and the shaft engaging part so related to the width of the recess that when the retaining element is moved longitudinally against the pressure of said yieldable means to withdraw the shaft engaging part out of the recess and is then partially rotated to position its shaft engaging part out of registering alignment with the recess, the shaft engaging part will engage upon the free edge of a marginal portion of the recess, and the retaining element will be held in elevated position to enable movement of the shaft end out of and into the recess.

6. In an apparatus of the character described including a frame member provided with a recess therein, a roller including a shaft having one end thereof removably disposed in said recess, and means for retaining said shaft end within said recess including a post member extending outwardly from the bottom wall of the recess, said post member being rigidly secured at its lower end directly to the bottom wall of the recess, a retaining element mounted on said post member

10
15
20
30

for movement along the same and for rotary movement thereabout, said retaining element having an elongated shaft engaging part of a width to permit the same to pass into said recess and engage said shaft end, yieldable means effective on said retaining element to urge the same inwardly along the post member and its shaft engaging part into said recess in engagement with said shaft end, and the shaft end engaging part of the retaining element being of sufficient length relatively to the width of the recess to engage upon the free edges of the side walls of the recess when the retaining element is moved longitudinally against the pressure of said yieldable means to withdraw its shaft engaging part out of the recess and is then partially rotated to position its shaft engaging part out of alignment with the recess, whereby the retaining element will be held in elevated position to enable free movement of said shaft end outwardly and inwardly of the recess.
